(57) **CLAIM**

The ornamental design for pneumatic vitreous cutting handpiece, as shown and described.

DESCRIPTION

FIG. 1 is a perspective view of pneumatic vitreous cutting handpiece showing my design;

FIG. 2 is a top plan view thereof;

FIG. 3 is a right side elevation view thereof, the left side elevation view thereof being a mirror image;

FIG. 4 is a bottom plan view thereof;

FIG. 5 is a front elevation view thereof; and,

FIG. 6 is a rear elevation view thereof.

The broken line showing of the cutter needle and aspiration and air pressure lines in FIG. 1 and broken line showing of the aspiration and air pressure lines in FIG. 3 are for illustrative purposes only and form no part of the claimed design.
